UNITED STATES PATENT OFFICE

167,401

CHRISTMAS LAMP ORNAMENT

Elizabeth A. Godber, Los Angeles, Calif.

Application December 16, 1950, Serial No. 13,469

Term of patent 3½ years

(Cl. D29—1)

To all whom it may concern:

Be it known that I, Elizabeth A. Godber, a citizen of the United States of America, residing in the city of Los Angeles, in the county of Los Angeles, State of California, have invented a new, original, and ornamental Design for a Christmas Lamp Ornament, or which the following is a specification, reference being had to the accompanying drawing, forming a part thereof.

Fig. 1 is a perspective view of a Christmas lamp ornament, showing my new design;

Fig. 2 is a bottom plan view thereof showing the supporting discs in position;

Fig. 3 is a view of the interior surface thereof as it appears when flattened; and

Fig. 4 is a view of the exterior surface thereof as it appears when flattened.

I claim:

The ornamental design for a Christmas lamp ornament, substantially as shown.

ELIZABETH A. GODBER.
